UNITED STATES PATENT OFFICE.

GEORGE WESTINGHOUSE, JR., OF PITTSBURG, PENNSYLVANIA.

FLUID-PRESSURE REGULATOR FOR AUTOMATIC BRAKES.

SPECIFICATION forming part of Letters Patent No. 240,062, dated April 12, 1881.
Application filed March 9, 1881. (No model.)

To all whom it may concern:

Be it known that I, GEORGE WESTINGHOUSE, Jr., of Pittsburgh, county of Allegheny, State of Pennsylvania, have invented or discovered a new and useful Improvement in Fluid-Pressure Regulators for Automatic Brakes; and I do hereby declare the following to be a full, clear, concise, and exact description thereof, reference being had to the accompanying drawings, making a part of this specification, in which—like letters indicating like parts—

Figure 1 is a vertical sectional view of my improved regulating device; and Fig. 2, by a diagram view of the main operative parts of an air-brake apparatus, illustrates the manner of its use.

In the construction and use of fluid-pressure brake apparatus it is exceedingly desirable that a uniform working-pressure be maintained at all times, as near as may be. Usually heretofore the engineer has had to rely on observing his pressure-gage for this purpose, and has had to start or stop his pump accordingly. It is highly desirable that the engineer be relieved from this care, especially as variations in working-pressure are liable to be greatest at times or in emergencies when his attention is required for other duties.

My present invention relates to regulating the speed and action of the pump automatically by variations in the working fluid-pressure which is stored up for use in operating the brakes, and as the principal use I propose practically to make of the invention is as a part of the Westinghouse automatic-brake apparatus I will first explain such use.

R, Fig. 2, indicates the main reservoir, and P the pump. The air-supply to the pumping-cylinder is represented at p , and the discharge-pipe leading to the main reservoir at p' . The ordinary operating-cock is shown at q , and the usual pipe-connections $q' q^2$ are made from it to the main reservoir and to the brake-pipe q^3 , which passes back beneath the cars with the usual hose and couplings between the cars. Beneath and connected with each car is an auxiliary reservoir, R' , brake-cylinder C , and triple valve R^2 , with the usual pipe-connections. These all have the construction and operation well known in the art.

My improved regulating device B has a pipe-

connection, b' , leading from the boiler and opening into the regulator at port B' . From the opposite port, B^2 , a pipe, b^2 , leads to the pumping-engine, and a third pipe, b^3 , leading from the brake-pipe q^2 or q^3 at any desired point back of the cock q , leads to a third port, B^3 . The regulator B has a double-ported U-shaped diaphragm, a , in the ports of which are seated the valves $a' a^2$, which together constitute a balanced valve. Both valves are on the same stem, and they are guided in their motion in any suitable way, as by a winged stem below and a straight stem playing in a socket above, as shown. A comparatively light spring, a^3 , is arranged to press the valves to or toward their seat.

In a chamber made about midway between the ends of the regulator I arrange a packed piston, D , and on its stem D' , I arrange a comparatively stiff or heavy spring, d , in such manner that its tendency will be to force the piston upward. While the lower end of the piston-stem is closed the remainder is hollow, and in the cavity is fitted a bushing, d' , suitable for guiding a stem, d^2 , one end of which rests against the bottom of the piston-stem cavity, and the other end bears against the lower end of the valve-stem, so that as the piston D goes down under the action of an excessive air-pressure applied to its upper end, as presently to be described, the valves will be free to be seated, either by their own weight or by the action of the spring a^3 , which is to be made strong enough for the purpose, and such seating of the valve will cut off the flow of steam from the boiler to the pumping-engine, and as such excessive pressure is relieved, so that the spring d (made sufficiently heavy for the purpose) shall cause the piston to rise, the valves will be unseated and steam will be admitted through the pipe b' , port B' , valve-ports, port B^2 , and pipe b^2 , to the engine-pump, to start it in operation.

In order that the excessive pressure in the brake-pipes (when it exists) may be brought to act on the end of the piston D , I provide in the lower part of the regulator a flexible diaphragm, g , arranged in a chamber, G , and properly secured at its edges to the case and at its center to a stem, g' .

Beneath the diaphragm and pressing up-

ward I arrange a spring, g^2 , and by means of a screw-nut, g^3 , I so regulate the resiliency or lifting-power of the spring that in its normal condition, and as against the desired working air-pressure, it will press the diaphragm up, and thereby hold to or nearly to its seat a valve, v , which is secured to the upper side of the diaphragm, and which opens and closes a line of ports, $s s' s^2 s^3$, which leads to the chamber s^4 above the piston D.

From the port B^3 , which by the pipe b^3 is in communication with the brake-pipe, a line of ports, $c c' c^2 c^3$, leads to the diaphragm-chamber G above the diaphragm.

In the usual or normal condition of the apparatus the valves $a a'$ will be slightly open, so as to let enough steam through to run the pump fast enough to keep up an ordinary working-pressure of, say, seventy pounds per square inch, more or less, as against loss by leakage. If, for any reason, the pump should operate so fast as to run up the air-pressure above that indicated, the excess of pressure, acting through the pipe B^3 and ports $c c' c^2 c^3$, will depress the diaphragm g more or less, according to the amount of such excess, open the valve v , and then the pressure following ports and passages s, s', s^2 , and s^3 will become operative in s^4 on the piston D, with the result of depressing it, and thereby leaving the valves $a a'$ free to come to their seats under the action of the spring a^3 . The steam will then be cut off and the pump will stop. As soon as, by leakage or by the lowering of air-pressure in the brake-pipes, (done for the purpose of applying the brakes,) the air-pressure in the brake-pipe falls below normal working-pressure a consequent reduction of pressure takes place in chambers s^4 and G, as a result of which the valve v is seated, and the spring d raises the piston D, and, acting through the stem d^2 , lifts the valves $a a'$, and lets steam onto the pump, so as to start it again in action. If the valve v should be thus seated before the pressure in s^4 is sufficiently reduced, ordinary waste by leakage will speedily reduce it to the desired extent. Hence the action or non-action of the pump depends on variation of air-pressure in the brake apparatus above or below normal pressure, so that a practically constant air-pressure will be preserved by the automatic action of the apparatus without requiring the constant care of the engineer.

In order to guard against the effects of leakage of fluid-pressure to parts of the regulator where its presence is not desirable, I provide leakage-ports $n n'$, as may be required.

The ports s^2 and c' are by preference made annular, and extend entirely around the case, in order that, as the parts composing the case are screwed together, the ports s' and s^3 , as also the ports c and c^2 , may be in communica-

tion, even if in screwing the parts of the case together such ports do not come into line with each other.

65

The same regulator may be employed as a part of a non-automatic fluid-pressure brake by connecting the pipe b^3 with the main reservoir, as illustrated by dotted lines z , Fig. 2, instead of with the brake-pipe; and the like connection with the main reservoir may be made even in the automatic brake, if so preferred, though less advantageously.

As one part of the novelty of the present apparatus consists in combining with a throttle or shut-off valve and a diaphragm and valve a piston subject to fluid-pressure on one side and a spring-pressure on the other, I include herein as of my invention such combination as herein shown, and all modifications thereof, with or without additions thereto, such as involve substantially a like operation, and particularly such modification as would adapt it for use as an element in the construction and operation of steam-engine governor-valves and air-compressing apparatus generally.

75

I claim herein as my invention—

1. A piston subject to fluid-pressure on one side and a spring-pressure on the other, in combination with a throttle or shut-off valve arranged to open and close the steam-flow to the engine, and a diaphragm and valve arranged to regulate the admission of fluid-pressure to the piston, substantially as set forth.

80

2. In combination with a fluid-pressure generator, auxiliary reservoir, and brake-cylinder of an automatic brake apparatus, a regulating-piston, throttle, diaphragm, and valve, arranged for conjoint action, substantially as set forth.

100

3. In combination with piston D, actuated by variations in fluid-pressure applied thereto, a balanced valve, $a a'$, actuated therefrom, and a diaphragm-valve, v , arranged to open and close the port through which air-pressure is admitted to the piston, substantially as set forth.

105

4. In combination with the continuously-charged pipe or reservoir of a fluid-pressure brake apparatus, a line of pipes and ports leading to one side of a movable diaphragm and thence to a piston-chamber, the piston whereof actuates the throttle or shut-off valve, a valve, v , arranged in such line of ports for opening and closing the same from the diaphragm motion, and a spring, g^2 , for moving the diaphragm on the diminution of air-pressure, substantially as set forth.

110

In testimony whereof I have hereunto set my hand.
